UNITED STATES PATENT OFFICE.

CARL J. ULMANN, OF NEW YORK, N. Y.

CHAIR.

1,303,994.

Specification of Letters Patent. Patented May 20, 1919.

Application filed March 8, 1917. Serial No. 153,245.

To all whom it may concern:

Be it known that I, CARL J. ULMANN, a citizen of the United States, and resident of the borough of Manhattan, city, county, 5 and State of New York, have invented certain new and useful Improvements in Chairs, of which the following is a specification.

My invention relates to chairs and more 10 particularly to that type thereof commonly known as reclining or tilting chairs and has for its object to provide a chair which may be shifted to and from a tilted or reclining position with a minimum of effort and 15 which, when in its tilted position comfortably supports all parts of the anatomy. A further object is to provide a chair construction in which the seat, in all positions of the chair, is located at a comfortable 20 height above the floor and in a position of maximum comfort to the person sitting in the chair. A further object of my improvement is to provide a chair of the indicated type with a foot rest which is readily and 25 automatically adjustable to comfortably accommodate the feet of persons of varying height. My invention further contemplates the provision of an efficient means whereby said foot rest is automatically actuated as 30 the chair is shifted to and from a reclining or tilted position. Other objects of my improvement will appear from the description hereinafter and the features of novelty thereof will be pointed out in the appended 35 claims.

In the accompanying drawings which, for illustrative and descriptive purposes, show an example of my invention, Figure 1 is a side elevation of my improved chair; 40 Fig. 2 is a vertical section showing said chair in one position; Fig. 2^a is a similar view showing the chair in its tilted position; Fig. 3 is a front elevation and Fig. 4 is a horizontal section on the line 4—4 of 45 Fig. 2.

As shown in the illustrated example the chair comprises a seat member 5 constructed for instance in the form of a frame and provided with a cane or other seat 6 to complete 50 the seat of the chair. A back frame 7 extends upwardly from the rear portion of seat member 5 preferably at a somewhat obtuse angle thereto and may similarly be provided with a cane or other back 8 to complete the back of the chair. The frame 7 may either form a continuation of the seat

member 5 or be secured thereto and in either case has the upper ends of its side members preferably projected upwardly and forwardly for instance along curved 60 lines as indicated at 9 to form supports for a head rest 10 secured in position in any suitable manner. At its front portion the seat member 5 is provided with a depending frame 11 extending downwardly and preferably forwardly at an inclination to said seat member 5 as shown in Figs. 1 and 2. The depending frame 11 is formed either as an integral part of said seat member or attached thereto in any suitable manner and 70 in the illustrated example is also provided with caning or the like 12.

The chair further comprises side frames having members 13 suitably attached to the seat member 5 and continuing members 14 extending upwardly and suitably connected with the back frame 7 as shown in Figs. 1 and 2. In addition, the side frames are formed with depending supports 15 and 16 respectively, the former being suitably 80 secured to the depending frame 11 and the latter preferably forming continuations of the members 13 and 15. If desired additional supports 17 may depend from the members 13 at intermediate points, said 85 supports 17 comprising either integral portions of the members 13 or being suitably attached thereto as may be preferred. At their lower ends the supports 15, 16 and 17 are combined either integrally or otherwise 90 with supporting rails 18 upon which the chair rests as shown in Figs. 1 and 2. The said rails 18 are each formed at their lower edges with straight front end portions 19 and straight rear end portions 20, the portions 19 and 20 being connected by intermediate curved portions 21 which extend in circular arcs described about points *a* corresponding or registering approximately to and with the combined center of 100 gravity of the chair and of the average occupant. In the empty chair the center of gravity is somewhat forward of the centers about which the curved portions 21 extend, so that said chair when empty will always 105 remain in an upright position. In the preferred form the supporting rails 18 are connected at their rear ends by a transverse bar 22 which may be curved as shown or otherwise shaped and which may be combined with said rails in any suitable manner. The chair may further include arm 110

rests 23 supported at their front portions for instance upon supports 24 extending up from the members 13, said arm rests having their rear ends, for instance, suitably connected with the back frame 7. If desired those portions of the back frame 7 which are adjacent to the arm rests 23 may be of relatively increased width as indicated at 7^a to form comfortable rests for the upper 10 arms of a person sitting in the chair. As shown in the drawings guideways 25 are located inside of and adjacent to the front depending frame 11 for the accommodation of slides 26 which have their lower 15 ends secured to and carry a foot rest 27 extending transversely across the chair as shown in Figs. 3 and 4; the slides 26 are preferably connected by means of a cross-bar or the like 28. As shown in Fig. 1 the foot 20 rest 27 may be wedge-shaped in cross-section and with the chair in the position shown in said figure, rests upon the floor or other surface upon which the chair is standing, the parts being combined and the chair being 25 constructed so that this result or an equivalent one is secured without interference with the intended upright position of said chair. In any case, the foot rest 27 preferably extends forwardly beyond the depending front 30 frame 11 so as to be easily available for its intended purposes at all times. Any suitable means may be provided for bringing about an automatic operation of the foot rest in the intended manner. For instance, as 35 shown in the illustrated example, the arrangement may include links 29 which at one end are pivotally connected at 30 to the foot rest 27 or to lugs 31 carried thereby, and which at their other ends are pivotally connected at 32 with actuating members 33. The latter are carried by a rod 34 rotatably mounted in the desired and proper location, as for instance by being journaled in bearings 35 secured to or forming part of the 40 supporting rails 18, said rod being provided with a recess 36 extending axially inward from one end as shown in Fig. 4. A torsional acting spring 36^a is located within said recess 36 and has its one end secured at 45 36^b within an aperture 18^a formed in the one rail 18 and its other end secured at 36^c to the rod 34; the exposed end of the aperture 18^a may be closed for instance by means of a suitable button 34^a in which case a similar button 34^b is secured to the other rail 18 at the corresponding point in order to balance the design and produce a proper finish. The actuating members 33 may be fastened to the rod 34 in any desired manner as for 50 instance by providing pins 33^a, each of which is arranged to pass through a radial aperture formed in each member 33 and adapted to register with a corresponding radial aperture formed in the rod 34. With this arrangement, it will be seen that the spring 55

36^a exerts a torsional tension tending to rotate the rod 34 and actuate the members 33 in a direction tending to always raise the foot rest 27. In order that the tension of said spring may be adjusted the rod 34 70 may be provided with a series of radial apertures for the accommodation of the pins 33^a; with this arrangement the rod 34 may be rotated to twist the spring 36^a until the desired tension has been secured therein after 75 which the pins 33^a may be inserted to secure the rod 34 and members 33 against relative movement.

It will of course be understood that the above construction is only an example and 80 that other arrangements producing equivalent results may be substituted if desired.

The actuating members 33 are formed with forwardly extending shoes 37 and are continued beyond the tube 34 in the form 85 of rearwardly extending shoes 38; in order to increase the rigidity of the construction the shoes 37 may be connected with each other by means of a cross-bar 39, while the shoes 38 are preferably connected by means 90 of a cross-bar 40. The shoes 37 and 38 which in practice preferably form integral parts of units each comprising an actuating member 33, a shoe 37 and a shoe 38, are arranged to engage the floor or other surface upon 95 which the chair is standing, for the purpose to be more fully described hereinafter.

In the forward or upright position of the chair, it rests upon the straight front portions 19 of the rails 18, with the parts in the 100 positions shown in Fig. 1. The said rails 18 are so proportioned and so located in the chair that the points at which the straight portions 19 terminate or connect with the curved portions 21 are in substantial registry, in a vertical direction with the points *a* which represent the centers of the arcs described by said curved portions 21 and which correspond or register approximately to and with the center of gravity of the chair when 105 occupied. The chair is thus supported in its forward or upright position and yet may be readily tilted the moment a person sits therein and leans against the back 7, this tilting operation being in consequence accomplished 110 without any visible effort on the part of said person and being substantially automatic. The tilting movement of the chair continues upon the curved portions 21 until the straight rear portions 20 of the rails engage 115 the floor or other surface upon which said chair is supported. In its tilted position, the chair thus rests upon said straight rear portions 20 with the back 7 and seat 6 tilted at such angles or occupying positions in which 120 a maximum comfort is assured to the person using the chair, the depending front frame 11 affording an adequate and comfortable support for the lower leg portions of said person. During the tilting movement of the 125 130

chair, the points *a*, or, in other words, the approximate center of gravity of the chair moves rearwardly in a substantially straight line in a horizontal plane, this being due to 5 the fact that the centers of the curved portions 21 register substantially with this point. The parts are so proportioned and located with respect to each other that in said tilted position the points at which the 10 rear portions 20 connect with the curved portions 21 are also in substantial registry in a vertical direction with the points *a* in their new positions. Owing to this fact, it is possible to return the chair to its forward or 15 upright position without any great effort being necessary on the part of the person sitting in the chair; at the same time the latter is firmly supported in its tilted position as long as the user thereof desires this, 20 the cross-bar 22 adding rigidity to the chair in this position. In addition to this, said cross-bar 22, by merging into the rails 18 along curved lines as is preferred, does away with sharp or abrupt ends and thus reduces 25 the danger of tripping over the projecting rear portions of the rails 18 when the chair is in either position and more particularly when it is in its upright position. In other words, anyone coming into unintentional 30 contact with said rails 18, near their rear end portions, either in the dark or otherwise, will simply slide or pass along said cross-bar 22 without injury and without tripping.

35 In addition to the above, if the construction is of the type illustrated, as the chair is tilted a pressure will be exerted upon the rear shoes 38, which, being held against downward movement by the surface upon which 40 the chair is resting, will in consequence rotate the tube 34, thus placing the spring 36 under a torsional tension or increasing the tension thereof as the case may be. This rotation of the tube 34 will cause the actuating members 33 to swing downwardly, which in turn will exert a downward pressure upon 45 the links 29 whereby the foot rest 27 will be forced downwardly, to a position which facilitates inserting the feet between the frame 50 11 and rest 27 so as to afford a comfortable rest for the feet of the person using the chair. During this operation the slides 26 travel downwardly in the guides 25, while the front shoes 37 may be raised from the 55 floor or other surface as shown in Fig. 2. The foot rest 27 is thus under a spring tension tending to raise it, and may thus be automatically adjusted to a position of maximum comfort to the person sitting in the 60 chair without regard to the length of the lower leg portions of said person.

As the chair is returned to its forward or upright position the forward shoes 37 will engage the floor or other surface in advance 65 of the foot rest 27 and will thus raise it

against any force exerted by the feet of the person using the chair, this action being assisted by the spring 36. The said foot rest 27 is thus prevented from engaging the floor or other surface as the chair is tilted for 70 wardly and assuming that the feet of the person in the chair remain in position thereon, whereby the danger of subjecting the slides 26 to a bending strain as the chair is swung forwardly is avoided. If the person 75 in the chair removes his feet from said foot rest the spring 36 will return said foot rest to its normal position, this operation of the spring taking place at any time after, and the moment the feet are removed from said 80 foot rest.

It will be seen that with my improved construction the chair seat may be positioned at a comfortable height from the floor or other surface and that the center of gravity 85 is maintained at a comparatively low point at all times, thus giving stability to the chair and avoiding the danger of overturning thereof and injury to the person sitting therein. Furthermore, the chair may be 90 brought from one position to the other without material effort on the part of said person and in its tilted position supports all parts of the anatomy in positions of maximum comfort and relieves any part of the body 95 from excessive strain. In addition, the chair is simple in construction and not likely to become disarranged and may be readily carried or moved from place to place.

100 In some cases the foot rest 27 and its co-operating parts may be omitted, the depending frame 11, in such instances, being relied upon to comfortably support the lower legs of the person sitting in said chair. It will, of course, be understood that the chair may 105 be suitably upholstered and that the details of construction and the particular form or design thereof may be varied in any desired manner or to meet the specific requirements of any particular use to which the chair is 110 to be put.

115 My improved construction provides an ideal rest chair which has many uses and which in addition may comprise an invalid chair having many and decided advantages.

120 Various changes in the specific form shown and described may be made within the scope of the claims without departing from the spirit of my invention.

I claim:

1. A tilting chair comprising a fixed seat, a back and means on which said chair is supported in a stationary, positive upright position independent of any force exerted by the seat and in a stationary, positive 125 tilted position independent of any force exerted by said seat and upon which said chair is tilted to and from said positions, said means extending continuously from the front to the back of the chair and being shaped 130

to cause the center of gravity of the occupied chair to move in substantially straight horizontal lines as the chair is tilted from one position to another.

- 5 2. A tilting chair comprising a fixed seat, a back and supporting means extending continuously from the front to the back of the chair and comprising front members whereby the chair is supported in a stationary, 65 10 positive upright position independent of any force exerted by the seat and continuing rear members whereby said chair is supported in a stationary, positive tilted position independent of any force exerted by the seat.
- 15 3. A tilting chair comprising a fixed seat, a back and supporting rails extending from the front to the back of the chair and comprising straight forward end portions on which said chair is supported in a stationary, 70 20 positive upright position independent of any force exerted by the seat, straight rear end portions on which said chair is supported in a stationary, positive tilted position independent of any force exerted by the seat, 75 25 and connecting curved portions on which said chair is tilted to and from said positions, said curved portions extending in arcs of circles having centers registering approximately with the center of gravity of said 80 30 chair when occupied.
- 35 4. A tilting chair comprising a seat, a back, supporting rails on which said chair is supported and tilted, an adjustable foot rest and means whereby said foot rest is automatically moved rectilineally toward and away from said seat as the chair is tilted from one 85 35 position to another.
- 40 5. A tilting chair comprising a seat, a back, supporting rails on which said chair is supported and tilted, an adjustable foot rest, a spring exerting a tension tending to raise said foot rest toward its normal position and means for positively moving said foot rest 90 45 downwardly to an operative position against the tension of said spring as the chair is tilted backward.
- 50 6. A tilting chair comprising a seat, a back, supporting means on which said chair is supported and tilted, a foot rest adjustable in rectilineal directions, actuating members operatively connected with said foot rest and shoes operatively combined with said actuating members whereby said foot rest is adjusted rectilineally as the chair is tilted backward.
- 55 7. A tilting chair comprising a seat, a back, supporting rails on which said chair is supported and tilted, a rectilineally adjustable foot rest, a spring exerting a tension tending to raise said foot rest toward its normal position, means for positively moving said foot rest to an operative position against the tension of said spring as the 100 60 latter is tilted forwardly.

chair is tilted backward and means for positively raising said foot rest toward its normal position as said chair is tilted forwardly. 105 65

8. A tilting chair comprising a seat, a back, supporting rails on which said chair is supported and tilted, means slidably mounted beneath said seat, a foot rest carried by said sliding means, actuating members, links connecting said actuating members with said foot rest, shoes operatively combined with said actuating members 75 whereby said foot rest is moved to an operative position as the chair is tilted backward and additional shoes operatively combined with said actuating members whereby said foot rest is moved toward its normal position as said chair is tilted forwardly. 80

9. A tilting chair comprising a seat, a back, supporting rails on which said chair is supported and tilted, means slidably mounted beneath said seat, a foot rest carried by said sliding means, actuating members, links connecting said actuating members with said foot rest, shoes operatively combined with said actuating members whereby said foot rest is moved to an operative position as the chair is tilted backward, additional shoes operatively combined with said actuating members whereby said foot rest is moved toward its normal position as said chair is tilted forwardly and a spring 95 90 for causing said foot rest to follow any adjustment of the feet of the person sitting in the chair.

10. A tilting chair comprising a seat, a back, supporting rails comprising straight forward and rear end positions and connecting curved portions extending in arcs of circles having centers registering approximately with the center of gravity of said chair, a front member depending from said seat to said rails and provided with guideways, slides movable in said guideways, a foot rest carried by said slides, actuating members pivotally mounted below said seat, links connecting said actuating members with said foot rest, a spring whereby said foot rest is moved toward its normal position, rearwardly extending shoes operatively combined with said actuating members for moving said foot to an operative position against the tension of said spring, and forwardly extending shoes operatively combined with said actuating members for moving said foot rest toward its normal position whereby contact between said foot rest in an operative position and the surface upon which the chair is resting is prevented as the latter is tilted forwardly. 110 105 115 120

In testimony whereof I have hereunto set my hand.

CARL J. ULMANN.
